UNITED STATES PATENT OFFICE.

EZRA S. POND, OF TOLEDO, OHIO.

GARBAGE-CAN.

No. 814,563.

Specification of Letters Patent.

Patented March 6, 1906.

Application filed November 16, 1903. Serial No. 181,273.

To all whom it may concern:

Be it known that I, EZRA S. POND, a citizen of the United States, residing at Toledo, county of Lucas, State of Ohio, have invented a certain new and useful Improvement in Garbage-Cans; and I declare the following to be a full, clear, and exact description of the invention, such as will enable others skilled in the art to which it pertains to make and use the same, reference being had to the accompanying drawings, which form a part of this specification.

The invention relates to improvements in garbage-cans.

15 The object of the present invention is to improve the construction of garbage-cans and to provide a simple and comparatively inexpensive garbage-can having an interior hopper and provided with a valve which is adapted to close the discharge-opening of the hopper and through which opening the garbage is adapted to pass in a sufficiently small and continuous stream to cause a downward draft of air that will continue during the entire discharge of the garbage from the hopper to the interior of the garbage-can.

With these and other objects in view the invention consists in the construction and novel combination and arrangement of parts 30 hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is a perspective 40 view of a garbage-can constructed in accordance with this invention, the outer lid or cover and the trough-like door being in their opened positions. Fig. 2 is a cross-section of the garbage-can, showing the same in place 45 against a fence or wall. Fig. 3 is a perspective view showing the bottom of the hopper and the valve of the latter.

Like characters of reference designate corresponding parts in all the figures of the 50 drawings.

A designates a rectangular can or receptacle provided at its upper edges with a metal strip A², adapted to strengthen and stiffen the can or receptacle at the top. The gar-

bage-can is provided with angle corner-pieces 55 A³, having horizontal lugs A⁴, formed by bending the outer ends of the front flanges of the corner-pieces outward. The can or receptacle is provided at its sides with suitable handles A⁵, one of which is shown in Fig. 1 of 6c the drawings. When the can is lifted to discharge its contents into a wagon, it is placed upon the edge of a wagon, the corner-pieces A³ sustaining the weight and concussion, if any, and the lugs A⁴ engaging the edge of the 65 wagon and preventing the can from slipping when the same is turned to discharge its contents.

Within the upper portion or mouth of the garbage can or receptacle is fitted an inverted 70 substantially frusto - pyramidal hopper B, having inclined or slanting walls B' and hinged at its back at B³ and provided around its upper edge with a flange b, which when the hopper is closed and in the position illustrated in Figs. 1 and 2 of the drawings rests upon the upper edges of the can or receptacle. The inclined walls or sides B' do not come together at the center, but leave a rectangular discharge-opening at this point. The rectangular discharge-opening is normally covered by a plate C, forming a valve and adapted to open downwardly. The plate C is hinged at the back to the bottom of the hopper at C², and the lower edges of the hopper 85 are turned outward to form a flat bearing-surface around the discharge - opening. A strip of felt or other suitable packing material is placed upon this surface and is secured to the flanges by bending the outer edges of 90 the latter downward and inward upon the strip. The engaging portions of the flanges of the bottom of the hopper are compressed to hold the packing-strip in position. The valve or plate C closes against the packing- 95 strip of felt to form a tight joint.

A bar C³ is riveted or otherwise secured to the lower face of the plate or valve C, and it extends beyond the side edges of the same to form laterally-projecting arms which are 100 connected to the lower ends of coiled springs C⁴. The springs C⁴ are secured at their upper ends to the upper portion of the opposite side walls of the hopper, and they are adapted to hold the plate or valve C normally against its seat. As an alternate construction, a torsional spring c⁴ may be used at the hinges of the plate or valve C. The valve

or plate C has also secured to it a bar C⁶, which is extended rearwardly and bent downwardly to provide a rearwardly-projecting inclined arm C⁷. A chain or wire C⁸ is secured to the outer end of the arm C⁷ and extends through a perforation in the upper portion of the rear wall of the hopper and is provided with a link or ring arranged at the upper face of the rear wall of the hopper and adapted to be readily grasped by the finger. By pulling upon the wire C⁸ the valve or plate C may be swung upon its hinges and opened.

The garbage can or receptacle is provided with an outer lid hinged at D² D² to the rear wall and adjacent to the point to which the hopper B is hinged. The upper edge of the rear wall of the garbage can or receptacle is provided with eyes, and the hopper and the outer lid have registering eyes to receive a pintle-rod which also passes through the eyes of the can or receptacle, whereby the outer lid and the hopper are caused to swing on a common pivot. A strip of felt is placed along the lower surface of the flange B to form a tight joint between the hopper and the upper edges of the sides of the can or receptacle. The lid, which forms a cover for the can or receptacle and also for the hopper, is held closely by a hook D³, as clearly illustrated in Fig. 2 of the drawings. The garbage can or receptacle is provided with a trough-like door E, having a rectangular face and segmental sides, which are turned up at their rear edges to form flanges or lugs E³. The flanges or lugs contact with bridges E⁴, under which the segmental sides of the trough-like door E pass in opening and closing the said door E. The door E is hinged at E⁵ to one side of the can or receptacle, and it acts as a valve to cover an opening E⁶ in the side to which the trough-like door is hinged. The strip of felt E² surrounds the opening E⁶ and receives the door E to form a tight joint. The trough-like door E is secured in its closed position by fastenings E², which are in the form of pivoted buttons. The garbage can or receptacle is placed against a fence or wall H to permit the hook B² to be disengaged by a person upon the inside of the wall or fence H. The said wall or fence is also provided with an opening H² to permit the door to be turned around upon its hinges through said opening, so that access to the can may be obtained from the outside of the wall H and the contents of the can removed by a shovel. The pivot or pintle E⁵ is placed somewhat above the bottom of the can, so that any moisture that may settle will be retained by the can. If desired, the bottom may be slanting, as indicated in dotted lines in Fig. 2 of the drawings.

The valve C is normally held closed by the spring C⁴. The garbage is placed in the hopper and the valve C is then opened by pulling

upon the wire or chain C⁸, thereby allowing the garbage to fall in the lower portion of the can or receptacle. When the garbage is discharged into the can or receptacle, the valve is allowed to close. When it is desired to remove the contents of the can, the door E may be turned downward and the removing-shovel inserted in the opening E⁶, or the trough-like door may be elevated in its closed position and the can removed, its upper end placed upon the edge of a wagon, the edge coming in contact with the corner-pieces A³, the hopper B and lid D being opened, and the bottom of the can turned upward to discharge the contents of the same.

It will be noticed that by using the hinged door E it is only necessary to cut a comparatively small hole in the wall or fence H and that the garbage in descending into the can will prevent any odor from escaping while the valve C is open. Also it will be seen that the valve C will close the can or receptacle when it is not held open and that the lid D will prevent any odor from escaping that may arise from material adhering to the hopper.

Having thus fully described my invention, what I claim as new, and desire to secure by Letters Patent, is—

1. In a garbage-can having an opening in the side thereof, a door hinged to the lower edge of said opening, having segmental sides adapted to slide outside of and in close engagement with the side walls of said can when said door is closed, said segmental sides being turned outward along their rear edges to form lugs, and a bridge secured to the can and passing over a segmental side so as to be contacted by its lug when the door is opened and so as to form a guide for a segmental side, substantially as described.

2. The combination of a can or receptacle, a hopper of frusto-pyramidal form fitted within the top of the can or receptacle and resting upon the upper edges thereof, a lid forming a cover for both the hopper and the can or receptacle, a valve consisting of a plate hinged to the hopper at the bottom thereof, arms extending laterally from the valve, springs connected with the arms and with the hopper for holding the valve normally closed, an inclined arm extending rearwardly from the valve, and an operating device piercing the rear wall of the hopper and connected with the rearwardly-extending arm.

3. The combination of a can or receptacle, a hopper of frusto-pyramidal form fitted within the top of the can or receptacle and resting upon the upper edges thereof, a lid forming a cover for both the hopper and the can or receptacle, said lid and hopper having a common hinge-joint, a valve consisting of a plate hinged to the hopper at the bottom thereof, arms extending laterally from the

valve, springs connected with the arms and with the hopper for holding the valve normally closed, an inclined arm extending rearwardly from the valve, and an operating device piercing the rear wall of the hopper and connected with the rearwardly-extending arm.

In testimony whereof I sign this specification in the presence of two witnesses.

EZRA S. POND.
